United States Patent Office.

JOHN L. BERNECKER, OF SAINT LOUIS, MISSOURI.

Design No. 2,745, dated August 13, 1867.

DESIGN FOR A TRADE-MARK.

The Schedule referred to in these Letters Patent and making part of the same.

TO ALL WHOM IT MAY CONCERN:

Be it known that I, JOHN L. BERNECKER, of the city and county of Saint Louis, in the State of Missouri, have originated and designed a new Design for a Trade-Mark, of which the following is a full, clear, and exact description, reference being had to the annexed drawing, making a part of this specification.

My design consists of an eagle with its wings extended, bearing upon its breast a shield, and holding in its talons two daggers crossed, in combination with the letters L and B and the conjunctive sign &, the whole being surrounded by the wreath A.

This design is intended to be used as an engraving or brand, and when used as the latter, the eagle, daggers, letters, and wreath will have such breaks in them as may be requisite to give the necessary strength to the spiral or other plate by which the impression is made.

What I claim as my invention, and desire to secure by Letters Patent, is—

The design for a trade-mark substantially as shown and described.

JOHN L. BERNECKER.
